ELECTRIC WATER HEATER

Joseph Novak, Roy, Wash.

Application September 19, 1939, Serial No. 295,591

5 Claims. (Cl. 219—39)

This invention relates generally to heaters, and particularly to an electric water heater.

The main object of this invention is to construct an electrically operated hot water air warming device which will be relatively small in size and light in weight and which gives off a relatively large supply of heat from a given current consumption within a very short space of time after the operation commences.

The second object is to utilize a special form of radiating element for the purpose of extracting the heat from the water which is directly heated by means of an electrical heating element.

These and other objects are accomplished in the manner set forth in the following specification as illustrated in the accompanying drawing, in which:

Fig. 1 is a side elevation of the device.

Fig. 2 is a front elevation thereof.

Fig. 3 is a vertical section taken along the line 3—3 in Fig. 4.

Fig. 4 is a section taken along the line 4—4 in Fig. 2.

Fig. 5 is a fragmentary side elevation of one of the heat radiating elements with a portion thereof broken away.

Fig. 6 is a transverse section taken along the line 6—6 in Fig. 5.

Fig. 7 is a diagrammatic view showing the relation of the elements involved in the device.

Similar numerals refer to similar parts throughout the several views.

Referring in detail to the drawing, there is shown a base 10 upon which is mounted a horizontal tubular boiler 11 within which is placed a low heat resistance element 12 and a medium heat resistance element 13. The elements 12 and 13 are connected to a three-heat switch 14 to which current is supplied from a line wire 15.

The elements 12 and 13 are connected by the wire 16 to a thermostat 17 which floats between the "warm" contact 18 and the "cold" contact 19, the former being connected to motor 20 of the fan 21 by means of a wire 22.

The contact 19 is connected by means of the wire 23 to the line wire 24 which connects to the second terminal of the motor 20.

Extending upwardly from the boiler 11 are the heat radiating tubes 25 which are preferably of the type provided with a plurality of fins 26, which owing to the manner of manufacture are approximately tangential and terminate in

sharp points 27 from which the heat flows readily.

It will be understood that the resistance elements 12 and 13 are suitably cased to protect same from the water 28 which is contained within the boiler 11 and the tubes 25. Water is supplied to the boiler 11 through the pipe 29 from the overhead supply tank 30 which acts as a safeguard as well as a gauge for if the water boils in the boiler 11, it will boil through the auxiliary tank 30 or if the pipe gets plugged by sediment the tank 30 constitutes a safety valve on the top of the radiating element.

The motor 20 and fan 21 are mounted in the casing 31 which is disposed behind the members 25. The case consists of the sides 32, 33 and 34 and the top 35 and encloses the heater down to the base 10.

If desired, a safety valve 36 is provided at the top of the element 25 which may be connected with a manifold 37, but this is not usually necessary. Shutters may be provided in the front 34 to deflect the air currents in the desired direction.

From the foregoing it will be seen by the use of this construction it is possible to employ a relatively small amount of water in the zone of heat, thereby making it possible to bring the radiator up to a heat delivering temperature in a small amount of time, after which the movement of the thermostat element 17 into engagement with the "warm" contact 18 will cause the motor 20 to operate and the air would flow past the fins 26, thereby carrying heat therefrom into the room being heated. The amount of heat being delivered to the boiler 11 depends on the heat of the three-heat switch 15, the switch being of the type commonly used on electric ranges whereby a small element 12 provides the low temperature, the large element 13 provides the intermediate temperature and both of the elements provide the high temperature; but whatever amount of heat is delivered to the boiler 11, the fan 21 is not operated until the desired boiler temperature is obtained.

Attention is drawn to my former Patent No. 2,151,140 of which this device is an improvement.

I claim:

1. A heater of the class described having in combination a horizontal immersion heater having upwardly extending radiating tubes communicated therewith, said heater containing a minimum amount of water, an elevated storage tank connected with said heater but not in cir-

culation therewith, means for circulating air past said radial element and means for thermostatically controlling the operation of said circulating means in response to temperature conditions.

2. An apparatus described in claim 1 together with means for selectively controlling the flow of heat to said heater.

3. An apparatus described in claim 1 characterized by having the radial tubes thereof provided with tangential fins adapted to dissipate the heat therefrom.

4. A device of the class described having in combination a base, a horizontal boiler of minimum capacity mounted on said base, a plurality of vertical tubes communicating with the interior of said boiler on the upper side thereof, said tubes having dissipating fins formed thereon

and an electric storage tank for supplying water to said boiler but not in circulation therewith.

5. A heater of the class described having in combination a base, a horizontal tube mounted on said base, a three-heat immersion heater mounted on said tube, a plurality of vertical tubes mounted on said horizontal tube in communication therewith, said vertical tubes having the upper ends thereof closed, an auxiliary water supply tank having a connection on the under side of said horizontal tubes, said tank and tubes being out of circulation, a motor driven fan for carrying the heat from said upright tubes, a thermostat responsive to the temperature of the water in said tubes for controlling the operation of said motor and means for controlling the flow of electrical energy to said heating element.

JOSEPH NOVAK.
